UNITED STATES PATENT OFFICE.

RHODES E. PULLEN, OF WINSTON-SALEM, NORTH CAROLINA.

RIBBON-REINKING ATTACHMENT FOR TYPE-WRITERS.

1,304,367.

Specification of Letters Patent. Patented May 20, 1919.

Application filed April 6, 1918. Serial No. 227,088.

To all whom it may concern:

Be it known that I, RHODES E. PULLEN, a citizen of the United States, residing at Winston-Salem, Forsyth county, and State 5 of North Carolina, have invented and discovered certain new and useful Improvements in Ribbon-Reinking Attachments for Type-Writers, of which the following is a specification.

10 The object of my said invention is to provide a method and means for re-inking and thereby prolonging the life and service of typewriter ribbons, the means being especially adapted for extemporaneous use and 15 without removing the ribbon from the machine. All as will be hereinafter more fully described and claimed.

Referring to the accompanying drawings which are made a part hereof, and on which 20 similar reference characters indicate similar parts;

Figure 1 is a perspective view of a ribbon inking attachment of a type adapted for practising my invention, as it appears in 25 position for use;

Fig. 2 a cross section,

Fig. 3 a perspective view of another form of device for the same purpose, and

Fig. 4 a top plan view of the same.

30 It is not deemed necessary to illustrate a typewriter with the device attached, being understood that the device may be supported on the typewriter frame by any convenient means. In Figs. 1 and 2, A represents a part 35 of the frame of a typewriter of common type (Remington) and B the ribbon as it appears coming through the aperture a and passing across the machine. The attachment consists of an ink well or cup 5 supported in a 40 bracket 6 on legs 7 by spring clamps 8. A pair of ink spreading rolls 9 are mounted on journals on a bracket 20 attached to one of the legs 7 and are positioned at a point where the ribbon B will conveniently pass between 45 them, as shown in Fig. 1.

In the construction of device shown in Figs. 3 and 4, the attachment is supported by a clamp 10 engaging at one end with a part of the frame, and at its other end with 50 an arm 11 secured to the upper part of the attachment support or post 12.

The attachment consists of a support or post 12 with a lateral bracket 13, with another support 14 at its outer end having a 55 shelf or rest 15 for a bottle of ink, and a

spring engaging clamp 16 on the upper arm of the bracket adapted to engage the neck of the ink bottle.

A bottle 17 containing ink of appropriate character is mounted on said shelf 15 and 60 has a closing member 18 of hollow form and extending down into the neck of the bottle. A tube 19 leads from one side of this closure member to a point adjacent to the top of post 12 and is formed with a spray nozzle on 65 its outer end. An air bulb 20 is connected by a tube 21 on the other side of the closure member as is shown.

On the upper end of post 12 is mounted a cross head 22 having upright journals 23 and 70 24 respectively on which rollers 25 and 26 are respectively mounted, a bowl shaped receptacle 27 is mounted near the upper end of said post 12 and immediately beneath said rollers.

In the operation of the device as shown in Fig. 1 the ink is fed to the ribbon B from cup A through a minute orifice extending from the lower end of the tube 21 forming a feed nozzle for said cup or well. The ribbon 80 with the line of fresh ink in its center passes between rolls 9, which are in close relationship, and is spread evenly and the ribbon surface left in a smooth condition, by the pressure of said rolls on opposite sides 85 thereof.

In the operation in the other form of device, as shown in Figs. 3 and 4, the typewriter ribbon is pulled outward from the rollers on which it is mounted on the machine and placed between the rollers 25 and 26 above the receptacle 27. Starting near one end of said ribbon the operator with one hand winds the ribbon from one roller to the other between the rolls 25 and 26 and 95 with the other hand by means of an air bulb sprays the ink upon the surface of the ribbon as indicated in Fig. 1. The rollers 25 and 26 bearing upon the surface of the ribbon operates to spread the ink over its surface 100 and to press out any surplus ink that may be deposited thereon making uniform distribution of the ink throughout the width and length of the ribbon, and leaving the surface of said ribbon smooth and even.

By use of this attachment it will be seen that the life of a typewriter ribbon may be prolonged until it is worn out, and a fresh and bright copy of the work obtained at all times.

105

110

Having thus fully described my said invention what I claim as new and desire to secure by Letters Patent is:

An attachment for typewriters for re-inking the ribbons thereof comprising a bracket attached to the frame of the typewriter, an ink reservoir supported by said bracket and provided with a discharge tube adapted to conduct the ink from the reservoir to the ribbon, and a pair of rollers between which said ribbon passes after the ink is deposited

thereon, whereby the ink is evenly distributed, substantially as set forth.

In witness whereof I have hereunto set my hand and seal at Winston-Salem, North Carolina, this 3rd day of April, A. D. nineteen hundred and eighteen.

RHODES E. PULLEN. [L. S.]
